UNITED STATES PATENT OFFICE

98,681

DESIGN FOR A DUMPY LEVEL

Adolph Langsner, Chicago, Ill., assignor to Eugene Dietzgen Company, Chicago, Ill., a corporation of Delaware

Application August 25, 1934, Serial No. 53,059

Term of patent 14 years

To all whom it may concern:

Be it known that I, Adolph Langsner, a citizen of the United States, residing at Chicago, Cook County, Illinois, have invented a new, original, and ornamental Design for a Dumpy Level, of which the following is a specification, reference being had to the accompanying drawing, forming part thereof.

Figure 1 is a side view of a dumpy level showing my new design;

Figure 2 is a plan view; and
Figure 3 is an end view taken from the right end of Figure 2.

I claim:
The ornamental design for a dumpy level as shown.

ADOLPH LANGSNER.
